United States Patent Office.

F. W. BROCKSIEPER, OF NEW HAVEN, CONNECTICUT, ASSIGNOR
TO SARGENT AND COMPANY, OF SAME PLACE.

Design No. 3,511, dated June 1, 1869.

DESIGN FOR A DRAWER-PULL.

The Schedule referred to in these Letters Patent and making part of the same.

To all whom it may concern:

Be it known that I, F. W. BROCKSIEPER, of New Haven, in the county of New Haven, and State of Connecticut, have invented a new Design for Drawer-Pull; and I do hereby declare the following, when taken in connection with the accompanying drawing, to be a full, clear, and exact description of the same, and which said drawing constitutes part of this specification, and represents a front view.

This invention relates to a design for a cast-metal drawer-pull; and consists in an oak sprig with acorns combined therein; and to enable others to fully understand my invention, I will proceed to describe the same as illustrated in the accompanying drawing.

A stem forms the lower centre, from which spring leaves to the right and left, and one upward, interspersed with which are acorns, all as fully shown in the accompanying illustration.

Having fully described my invention,

What I claim, and desire to secure by Letters Patent, is—

The design for a drawer-pull, as herein described and illustrated.

F. W. BROCKSIEPER.
